(57) **CLAIM**

The ornamental design for a pruning tarp, as shown and described.

DESCRIPTION

FIG. 1 is a perspective view of a pruning tarp shown in an open position which includes a hole and flap with a hook and loop fasteners along the flap.

FIG. 2 is an enlarged view of a portion of FIG. 1;

FIG. 3 is a top view of the pruning tarp of FIG. 1 with the flap closed;

FIG. 4 is a bottom view of the pruning tarp of FIG. 1 with the flap closed;

FIG. 5 is an enlarged view of a portion of FIG. 5;

FIG. 6 is a front view of the pruning tarp of FIG. 1 with the flap closed;

FIG. 7 is a rear view of the pruning tarp of FIG. 1 with the flap closed;

FIG. 8 is a right side view of the pruning tarp of FIG. 1 with the flap closed; and,

FIG. 9 is a left side view of the pruning tarp of FIG. 1 with the flap closed.

The broken lines shown along a perimeter of the tarp, along the flap, and along a perimeter of the hole represent stitching and form a part of the claimed design.
